 The Murray Corporation of America, a corporation of Delaware

Application February 7, 1936, Serial No. 62,731

4 Claims. (Cl. 280—163)

This invention relates to threshold constructions for automotive vehicles. More particularly, it relates to a novel form of threshold construction which provides a resilient covering not only extending over the entire surface of the running board, but extending inwardly of the door opening to the interior of the body.

It is a general object of the present invention to provide a threshold construction which is relatively simple, economical of manufacture, easy of installation and which, at the same time, effects an exceedingly tight and efficient seal with respect to the doors with which it is associated.

Yet another object of the present invention consists in the provision of a threshold construction in which the covering for the running board extends inwardly sufficiently far to mate with the floor covering of the interior of the body.

Still further the present invention contemplates the provision of a vehicle body construction in which the running board is preformed to provide a vertically disposed wall against which the doors of the vehicle mate rather than providing a jamb face at the lower edge of the door opening.

The present invention further contemplates the provision of a novel running board construction in which the running board is formed of an integral metal stamping which extends upwardly and over the side sill of the vehicle body and is secured interiorly of the body in substantially the plane of the floor thereof.

Yet another object of the present invention consists in the provision of a novel threshold construction affording a neat exterior appearance in vehicle bodies in which no running board is used.

Many other and further objects and advantages of the present invention will become apparent from the following specification when considered in connection with the accompanying drawing forming a part thereof.

In the drawing:

Fig. 1 illustrates an automobile body of the type particularly adaptable for construction in accordance with the present invention.

Fig. 2 is an enlarged fragmentary view partly in section, illustrating the manner in which the improved running board construction mates with one of the side sills of the vehicle and the manner in which one of the vehicle doors mates with the running board.

Fig. 3 is a reverse fragmentary perspective view of the improved running board and sill construction adjacent the central pillar showing the man-

ner in which the resilient covering material mates interiorly of the body adjacent the central pillar structure.

Fig. 4 is a fragmentary perspective view partly in section, illustrating in detail the manner in which the central pillar is secured to the sill of the chassis and the manner in which the resilient covering material is disposed about the pillar.

Fig. 5 illustrates a modified form of the invention illustrated in the preceding figures, in which a sill construction is shown for an automobile body in which no running board is used.

In the specific form of the invention illustrated in the drawing, the structure shown comprises a sill formed of a member of outwardly presenting channel section 10 which is reinforced by a substantially vertically disposed face plate 11 which may be secured to the channel member 10 by welding or other suitable means, such as are conventional in the art. The sill member 10 serves to support one side of a horizontally extending floor 12 which, as is conventional in the art, may be formed of metal or other suitable similar material, and which serves to constitute a floor for the interior of the vehicle.

The improved running board construction comprises a sheet metal member 15 which is preferably beaded or rolled over in its outer marginal edge at 16 to provide a structure of increased strength. This member 15 preferably extends horizontally inward toward the vehicle to provide a suitable flat running board surface and is then bent upwardly and then inwardly over the mating flanges of the members 10 and 11. The inner marginal edge of the member 15 is then bent downwardly and horizontally in substantially the plane of the floor 12 to provide a securing flange 17 which may be fastened to the upper surface of the sill member 10 by means of suitable bolts 18.

In vehicles which have two doors on a side, it is essential that a pillar be disposed between these two door openings and this pillar is preferably supported at its lower end upon the sill member 10.

In order to provide a strong, effective mounting for the lower end of the pillar structure, a substantially channel-shaped boss or bracket 20 is flanged at 21 in its marginal edges and secured through these flanges 21 to the face plate 11 of the sill structure. This bracket 20 provides a boss over which the lower end of a channel shaped pillar 22 fits and to which the lower end of the pillar may be directly secured by welding or other suitable means. The running board 15

is provided with a suitable slot or aperture which closely fits the pillar 22 and permits the mounting of the running board in place after the pillar has been secured in position. It will be apparent from the above described construction that the bracket 20 terminates at its upper end substantially flush with the upper edge of the face plate 11 and consequently the pillar structure extends through the vertically disposed portion of the running board structure rather than through the horizontally disposed portion thereof.

As is conventional in the art, the vehicle body is provided with suitable doors 25 which serve to close the door openings and these doors are preferably provided at their lower marginal edges with a resilient sealing element 26 which serves to mate with the vertically extending surface of the running board structure in order to provide an effective and tight closure of the door and door opening at this point.

In order to protect the running board and threshold structure from abrasive wear and provide a neat and attractive appearance, I find it preferable to cover the entire running board member with a resilient covering of rubber or similar suitable material 30 which may be vulcanized thereon, or otherwise suitably secured thereto. This resilient covering preferably covers the entire upper surface of the running board structure except the inwardly extending flange 17, and it will therefore be seen that the resilient covering mates neatly with the lateral edge of a carpet 31 such as is conventionally used on the floor of the vehicle body. Adjacent the pillar structure interiorly of the vehicle, the resilient covering material is extended out substantially beyond the running board structure to provide mating flaps 32 and 33 which serve to cover the space over the bracket 20 internally of the pillar 22.

It will therefore be clear that the rubber covering material may be applied to the running board structure prior to the installation of the running board on the car and the flaps 32 and 33 may

be bent back to allow the insertion of the running board into engagement with the sill structure and permit the passage of the pillar between the two flaps. After the running board is installed, the flaps may be folded down into mating engagement to provide a neat structure interiorly of the vehicle body.

What is claimed is:

1. In a vehicle body construction having a door opening therein, a sill beneath said opening, a running board secured to the top of said sill and preformed to provide a threshold for said door opening, and a resilient covering for said running board also extending through said door opening and covering said threshold.

2. In a vehicle body construction having a pair of door openings in the side thereof, a sill beneath said door openings, a pillar extending upwardly from said sill between said door openings, a running board having projecting portions extending through said doorway openings and secured to said sill, said projections being preformed to provide thresholds for said doorway openings and being covered with resilient material.

3. A vehicle body having a door opening therein, a door for said opening, a sill at the lower side of said opening and a running board extending inwardly over the upper side of said sill and secured thereto, the lower marginal edge of said door being adapted to engage said running board when the door is in closed position.

4. In a vehicle body having a door opening therein, a door for said opening, a sill at the lower side of said opening, a running board having its inner marginal portion extending over said sill and secured to the upper side thereof, said running board being offset downwardly adjacent said sill and projecting horizontally outwardly from said downward offset, the lower marginal edge of said door being adapted to engage the offset portion of said running board when the door is in closed position.

WALTER C. HOFFMAN.
